UNITED STATES PATENT OFFICE.

EDWARD J. ZAHNER, OF CANTON, OHIO.

DOOR-CASE FASTENER.

1,179,597.

Specification of Letters Patent. Patented Apr. 18, 1916.

Application filed February 6, 1915. Serial No. 6,408.

To all whom it may concern:

Be it known that I, EDWARD J. ZAHNER, a citizen of the United States, residing at Canton, in the county of Stark and State of Ohio, have invented a new and useful Door-Case Fastener, of which the following is a specification.

My invention relates to improvements in fastening devices for attaching sheet metal door cases, window frames and the like and has more especial reference to a device of the character referred to in which no screws or bolts are visible after the structure has been assembled.

5 The object of my invention is to provide a device of the character described which is adapted to be used for attaching metal door cases and the like and in which no screws or bolts will be visible.

10 Another object is to provide a fastener of the character referred to in which a vertical and horizontal adjustment of the door case may be made before the structure is permanently attached.

15 With these objects in view the invention consists in the novel construction and arrangement of parts, hereinafter described, illustrated in the accompanying drawings, and particularly pointed out in the appended claims, it being understood that various changes in the form, proportions, size and minor details of construction may be made within the scope of the appended claims without departing from the spirit 20 or sacrificing any of the advantages of the invention.

25 In the accompanying drawings: Figure 1 is a horizontal sectional view through a portion of a door case, showing the fastener attached thereto. Fig. 2 is a section on line 2—2, Fig. 1. Fig. 3 is a fragmentary view of the inner face of the buck to which the door case is attached. Fig. 4 is a detail perspective view of the slotted bracket which 30 forms a part of the fastener. Fig. 5 is a detail perspective view of the bolt used in the fastener. Fig. 6 is a detail perspective view of the split nut which engages the bolt. Fig. 7 is a detail perspective view of the reverse side of the nut.

35 Similar numerals of reference indicate corresponding parts throughout the several figures of the drawing.

40 Referring more specifically to the construction illustrated in the accompanying

drawings, the numeral 1 indicates a portion of the buck to which the door case is attached.

45 The numeral 2 indicates the door jamb and the numeral 3 the outer frame of the door case. The slotted bracket 4 which is provided with a centrally located horizontally, disposed off-set portion 5 in which is located a longitudinal slot 6, is attached to the frame 3 as hereinafter described. A 50 plurality of the brackets such as are indicated by the numeral 4 are attached at intervals around the frame 3, the brackets being spot-welded to the frame.

55 Located through the slot 6 of each bracket 70 is a soft iron bolt 7, the head 8 of which is located within the off-set portion 5 of the bracket, the bolt being slidably mounted within the slot 6. A split nut 9 is carried upon the outer screw threaded extremity 75 of each bolt, the nut being provided with an annular groove 11, the purpose of which will be hereinafter described. The nut 9 is split longitudinally throughout its entire 80 length as indicated at 12 and diametrically opposite thereto, the forward conical extremity 13 of the nut is split as indicated at 14. For a purpose hereinafter described these nuts are made of case hardened steel or 85 similar material.

90 Located at intervals around the buck 1 is a plurality of key hole slots each of which consists of an enlarged aperture 15 and a vertically disposed slot 16 communicating therewith, each of said key hole slots being 95 adapted to register with one of the nuts 9 carried upon the bolts 7, when the frame 3 is placed in position to be attached to the buck. The frame 3 is raised into position adjacent the buck 1, the nuts 9 upon the 100 bolts 7 being passed through the enlarged apertures 15 of the key hole slots, the frame then being lowered slightly, the groove 11 of each nut engaging the vertical slot 16 of the adjacent key hole slot. Sufficient vertical adjustment of the door frame is possible by means of the vertical slots 16 and sufficient horizontal adjustment thereof by means of the slots 6 in the brackets 4. When the frame has been properly adjusted 105 and is ready for permanent attachment it is only necessary to tap the frame at the point where each of the bolt heads 8 contacts therewith. The nuts being held stationary within the slots 16, the bolts will be driven 110

- through the nuts and owing to the fact that the nuts are split they will open allowing the bolts to pass over the internal threads thereof and when the frame has 5 been brought tightly against the buck it will be permanently held there, the internal threaded portion of each nut biting into the soft iron bolt and holding the same against displacement.
- 10 Thus it will be seen that by the construction herein described and illustrated a fastener is provided for attaching sheet metal door cases and the like in which a vertical and a longitudinal adjustment of the door 15 case may be made before it is permanently secured and in which no bolts or screws are visible upon the finished structure and which will securely hold the door case against displacement.
- 20 Although the drawings and above specification disclose the best mode in which I have contemplated embodying my invention I desire to be not limited to the details of 25 such disclosure for, in the further practical application of my invention, many changes in form and construction may be made, as circumstances require or experience suggests, without departing from the spirit of the invention, within the scope of the appended 30 claims.
- I claim:
1. A device of the character described, comprising a buck provided with a vertical slot, a metallic frame, a bracket secured to 35 said frame, said bracket provided with a horizontal slot, a bolt carried in said bracket and extending through the slot therein, and a nut carried upon the extremity of said bolt, said nut being adapted to be 40 located in the slot in said buck.
  2. A device of the character described, comprising a buck provided with a vertical slot, a metallic frame, a bracket welded upon said frame, an off-set channel portion 45 provided upon said bracket, said channel portion having a horizontal slot therein, a bolt located through said horizontal slot, the head of said bolt being located within the channel portion, and a nut carried upon 50 the extremity of said bolt, said nut being adapted to be located through the slot in said buck.
  3. A device of the character described, comprising a buck provided with a vertical key hole slot, a metallic frame, a bracket welded upon said frame, a channel portion provided upon said bracket, said channel portion having a horizontal slot therein, a bolt located through said horizontal slot 55 60 the head of said bolt being located within the channel portion, and a split nut carried upon the extremity of said bolt, said split nut being adapted to be moved over the threads of said bolt, said nut being adapted 65 to be located within the slot in said buck.
  4. A device of the character described, comprising a buck provided with a vertical key hole slot, a metallic frame, a bracket welded upon said frame, a channel portion provided upon said bracket, said channel portion having a horizontal slot therein, a bolt located through said horizontal slot, the head of said bolt being located in said channel portion, and a split nut carried upon the extremity of said bolt, said split nut being adapted to be moved over the threads of said bolt, said nut being provided with an annular groove adapted to register with the vertical slot in said buck. 7
  5. A device of the character described, comprising a supporting member provided with a vertical slot, a metallic plate, a bracket secured to said plate, said bracket provided with a horizontal slot, a bolt carried in said bracket and extending through the slot therein, and a nut carried upon the extremity of said bolt, said nut being adapted to be located in the slot in said supporting member. 8
  6. A device of the character described, comprising a buck provided with a vertical slot, a metallic frame, a bracket secured to said frame, said bracket provided with a horizontal slot, a bolt carried in said bracket and extending through the slot therein, and a nut carried upon the extremity of said bolt, said nut being provided with an annular groove adapted to register with the vertical slot in said buck. 9
  7. A device of the character described, comprising a buck provided with a vertical slot, a metallic frame, a bracket secured to said frame, said bracket provided with a horizontal slot, a headed pin carried by said bracket and extending through the slot therein, and a collar carried upon the extremity of said pin, said collar being adapted to be located in the slot in said buck and adapted to frictionally engage said pin at any desired point. 10
  8. A device of the character described, comprising a buck provided with a vertical slot, a metallic frame, a bracket secured to said frame, said bracket provided with a horizontal slot, a headed pin carried by said bracket and extending through the slot therein, and a collar carried upon the extremity of said pin, said collar being provided with an annular groove adapted to register with the vertical slot in said buck 11 and adapted to frictionally engage said pin at any desired point. 11
  9. A device of the character described, comprising a buck provided with a vertical key hole slot, a metallic frame, a bracket secured to said frame, said bracket provided with a horizontal slot, a headed pin carried in said bracket and extending through the slot therein and a collar carried upon the extremity of said pin and adapted to be 125 130

passed through the enlarged portion of the key hole slot in said buck, said collar being provided with an annular groove adapted to register with the vertical slot in said buck and adapted to frictionally engage said pin at any desired point.

5 In testimony that I claim the above, I have hereunto subscribed my name in the presence of two witnesses.

EDWARD J. ZAHNER.
